OFFSET ROTARY COPYING MACHINE

Leo Kluitmann, Dusseldorf, Germany

Application July 21, 1937, Serial No. 154,894
In Germany July 24, 1936

7 Claims. (Cl. 101—144)

By the patent application Serial No. 549,867, filed July 10, 1931, a rotary copying machine with a copyable original in mirror script fixed on a printing drum for printing moistened sheets has become known, in which the original in mirror script fixed on the printing cylinder is automatically changed without stopping of the printing drum, in that for instance grippers which securely hold the original on the printing cylinder 10 are automatically opened, a fresh original lying for instance on a table being automatically fed to the grippers whereupon the grippers close and securely hold the fresh original.

The invention opens a new range of application 15 for the device for changing originals described and claimed in the prior specification, and according to the invention the device for changing the original as disclosed by the prior application is employed in offset rotation copying machines 20 with an original fixed on a printing cylinder.

If the printing original changing device known per se is used in offset rotary duplicating machines, there is provided according to the invention for the transfer cylinder (rubber cylinder) 25 an automatic ink removing and cleaning device, which cleans the circumferential surface of the transfer cylinder before beginning to print with the fresh printing original so that after changing the printing original, the fresh printing original 30 is immediately printed perfectly on the sheets or the like.

The originals have been fixed in this machine up to the present by means of perforations and pins on the printing cylinder and by hand. If 35 an original had to be changed, it was necessary to detach the original by hand from the pins and besides to clean the transfer cylinder, in order that after the insertion of the fresh original only the ink transferred from the fresh original upon 40 the transfer cylinder be transmitted upon the sheet to be printed. The changing of an original demands therefor in the offset rotation copiers of known type very much time and requires every time a stopping of the machine.

45 The invention offers in comparison with the known offset rotation copying machines the great advantage that in economical manner in shortest time even small numbers of copies can be produced. The changing of original is effected according to this invention absolutely automatically 50 without stopping of the printing machine.

The invention can be carried out in different manners. The arrangement may be for instance such that the transfer cylinder (rubber cylinder) 55 is continuously freed from ink and cleaned

during the printing process by a brush cylinder or the like, preferably rotating in a direction opposite to that of the rubber cylinder, said brush cylinder being arranged between the printing point and that point on which the intermediate 5 print is transmitted onto the rubber cylinder. In offset rotation copying machines it becomes therefor necessary for the first time to provide an ink removing and cleaning device for the transmitting roller. In this manner it has to be made 10 possible to employ also in offset copying machines the original exchanging device according to the prior specification.

Only by the invention it is attained that after 15 the original has been changed the fresh original is immediately printed perfectly. The invention may however be carried out in such a manner that two transfer cylinders (rubber cylinders) are provided which are controlled automatically 20 in dependency on the change of original in such a manner that actually the one cylinder is employed for the printing whilst the other cylinder is being cleaned. Also in this instance the cleaning of the cylinder can be carried out by brush cylinders or the like rotated in a direction opposite to the cylinder to be cleaned.

25 By the invention it is therefore rendered possible to employ the automatic changing of original without stopping of the machine also in offset rotation copiers and to thereby make these 30 machines work economically also for smaller editions.

An offset-rotation copying apparatus is shown 35 in the accompanying drawing, by way of example, in which two rubber cylinders are provided.

Fig. 1 shows a side elevation of the copying apparatus, and

Fig. 2 a front view of the same.

In the machine shown in the drawing the cylinder 1 carries the original. The machine comprises further two transfer cylinders (rubber cylinders) 2 and 2a, and an impression cylinder 3 which presses the paper sheet 35 to be printed against the rubber cylinder 2, 2a respectively. The cylinder 3 is journalled in bearings 8 which 40 are guided in the machine frame 39 and pressed in upward direction by springs 9. The transfer cylinders 2 and 2a are journalled in bearings 5 guided in two guide bars 4 and pressed by springs 6 in upward direction against the cylinder 1. The 45 guide bars 4 can be brought on their beds 38 into two different positions so that, in the one position the one rubber cylinder and in the other position the other rubber cylinder is in the operative position necessary for the printing. In both these 50 55

positions the guide bars 4 are secured in their position by stopping balls 7 pressed on by means of springs. Felt pads 10 filled with a suitable liquid for cleaning the transfer cylinder which is 5 actually not employed for printing are provided. These felt pads may either be pressed against the cylinder by hand by the operator of the machine or by spring pressure. The two transfer cylinders 2 and 2a are coupled by a chain- or wedge belt 10 drive 37, so that the cylinder not actually employed for printing is rotated by the cylinder actually in working position and cleaned by the corresponding felt pad 10. The inking mechanism is shown generally at 11 which may be of 15 any well known construction and include an inking roller 12 adapted to engage the cylinder 1.

Two double armed levers 13 serve for controlling the guide bars 4, one arm of said levers having a slot engaging over a stud 13a of the guide bars 20 4, said levers being mounted on the axle 14 of the printing cylinder. The two other arms of the 20 levers 13 have slots 40 of a special shape, said slots engaging over pins 16 of the control cranks 15. These control cranks 15 are keyed on the 25 axle 17, on which a spur wheel 18 is mounted axially shiftable but not turnable. This spur wheel 18 can be brought by axial shifting into engagement with a toothed segment 19 fixed on the cylinder 1. Normally, the spur wheel 18 is 30 kept out of gear by a spring 18b mounted on the axle 17 and supported by a collar 18a. Owing to the slots 40 engaging over the pins 16 of the cranks 15 it is ensured that, during a semi-rotation of the cranks, the rubber cylinder 2 which is 35 in the operative position is brought into the cleaning position and that simultaneously the rubber cylinder 2a being in the cleaning position is brought into the operative position.

The arrangement is such, that the devices employed for controlling the mechanism for changing the original serve at the same time for bringing the spur wheel 18 serving for altering the position of the rubber cylinder into gear with the toothed segment 19.

45 In the copying machine of known type a carriage 20 with a curve 29 is lifted by depressing of a lever 21, the table plate 30 being lowered at the same time and brought into the range of catches provided on the printing cylinder, 50 grippers 42 mounted on an axle 26 being at the same time opened by the upward movement of a roller 43 fixed on lever 27. In the copying machine according to the invention the carriage 20 has at its upper portion an inclined surface 23 55 designed to influence a roller 24a mounted at the end of lever 24. This lever 24 is oscillatably mounted in a bracket 25 on frame 39 of the machine. By actuating the handle 21, the carriage 20 is lifted, the inclined surface 23 presses in side 60 ward direction the roller on the lever 24 and thereby shifts the spur wheel 18 over a wedge on the axle 17 into its engaging position.

The paper to be printed is introduced by hand or in known manner automatically from a pile 65 35 to between the pressing on cylinder 3 and the rubber cylinder 2 and laid after the printing onto the table plate 36.

The operation of the arrangement described is as follows:—

70 If the original has to be changed, the lever 21, pivotally mounted on the fulcrum 41, is depressed, and thereby the carriage 20 is lifted. If, during the rotation of the cylinder 1, the crank 27 of the crank shaft 26 comes into the range of the curve 75 29, the grippers 42 are opened and the clamped

original is released. The released original falls upon a delivery table (not shown) arranged parallel to the table 30 at the height of the tangential plane of the cylinders 1 and 2. At the same time the front portion of table 30 is 5 lowered relative to the printing cylinder and the new original is fed to the grippers in known manner. At this moment the printing from the original already liberated by the grippers is not yet completely finished so that it is necessary to 10 maintain in operation the rubber cylinder 2, which is in its operative position, until the printing from the original has been completed. Whereas the two rubber cylinders 2 and 2a still remain in their previous position, the new original 15 is gripped by the grippers and drawn along by the printing cylinder 1. At the moment at which the printing from the original to be removed has 20 been completed, the two rubber cylinders 2 and 2a must be brought into the second position. The toothed segment 19 is therefore arranged on the cylinder 1 displaced by such an angle relative to the gripper shaft 26, that accurately at this moment the shifting of the rubber cylinders takes 25 place. The ratio of transmission between the toothed segment 19 and the spur wheel 18 and the length of the toothed segment 19 are selected so that, when the two parts come into gear, the spur wheel 18 is rotated by one half-rotation, and so that this semi-rotation has already been 30 completed, when the upper end of the fresh original comes into the range of the rubber cylinder 2.

During the half rotation of the spur wheel 18 the shaft 17 and also the two control cranks 15 35 keyed on this shaft are turned by 180°. During the rotating of the cranks 15 the studs 16 engaging into the slots 40 of the levers 13 cause an oscillation of the double-armed levers 13 and thereby the desired shifting of the rubber cylinders 2 and 2a. As the rubber cylinder 2 or 2a 40 respectively, which has just been shifted into the operative position, has previously been in the cleaning position, it is perfectly freed from ink and can now be employed for printing from the 45 fresh original. The rubber cylinder 2, which has just been employed for the printing, is now in the cleaning position and is freed from ink and cleaned by the felt pad 10 saturated with a cleaning liquid. After the hand lever 21 has 50 been liberated, it descends under the action of spring 22 again into the initial position, the carriage 20 and the inclined surface 23 being also lowered again, so that, under the action of spring 18b, also the spur wheel 18 returns into the normal 55 position.

The curve-like construction of the slots 40 is necessary in order to make it possible that the cranks 15 with the rollers 16, during the turning in the lower semicircle, can freely pass through 60 in the first and last third. If the slots were parallel, the cranks 15 with the roller 16 would effect in the lower semicircle in the first third at about 45° and in the last third at about 135°, abnormal movement of the carriages 4 and the 65 cylinders 2 and 2a mounted thereon.

I claim:—

1. In an offset copying machine, a printing cylinder, means for securing a foil on the printing cylinder, an offset cylinder, the combination 70 of means operatively connected to the printing cylinder for moving the offset cylinder into and out of active position with respect to the printing cylinder, with means for cleaning the offset cylinder when it is in inactive position.

2. In an offset copying machine, a printing cylinder, means for securing a foil on the printing cylinder, a pair of offset cylinders, means operatively connected to the printing cylinder 5 for alternately moving one of the offset cylinders into active position with respect to the printing cylinder, and means for cleaning that offset cylinder which is in inactive position at the time.
- 10 3. In an offset copying machine, a frame, a printing cylinder, a slide mounted for reciprocation in the frame, a pair of offset cylinders mounted on the slide, means operatively connected to the printing cylinder for shifting the 15 slide for alternately moving one of the offset cylinders into active position with respect to the printing cylinder, and means for cleaning that offset cylinder which is in inactive position at the time.
- 20 4. In an offset copying machine, a frame, a printing cylinder, a slide mounted for reciprocation in the frame, a pair of offset cylinders mounted on the slide, a crank operatively connected to the printing cylinder, a double-armed 25 lever having a cam slot adapted to be engaged by the crank in one of its arms and operatively connected to the slide with its other arm for shifting the slide for alternately moving one of the offset cylinders into active position with respect to the printing cylinder, and means for 30 cleaning that offset cylinder which is in inactive position at the time.
5. In an offset copying machine, a frame, a printing cylinder, a slide mounted for reciprocation in the frame, a pair of offset cylinders 35 mounted on the slide, a crank, a clutch operatively connecting the crank to the printing cylinder, manually operated means for controlling the clutch, a double-armed lever having a cam slot adapted to be engaged by the crank in one 40 of its arms and operatively connected to the slide with its other arm for shifting the slide
- for alternately moving one of the offset cylinders into active position with respect to the printing cylinder, and means for cleaning that offset cylinder which is in inactive position at the time. 5
6. In an offset copying machine, a frame, a printing cylinder, a slide mounted for reciprocation in the frame, a pair of offset cylinders mounted on the slide, a crank shaft, a pinion splined on the crank shaft, a toothed sector on 10 the printing cylinder whose length is equal to one-half of the pinion's perimeter, manually operated means for shifting the pinion into mesh with the sector, a crank on the crank shaft, a double-armed lever having a cam slot adapted 15 to be engaged by the crank in one of its arms and operatively connected to the slide with its other arm for shifting the slide for alternately moving one of the offset cylinders into active 20 position with respect to the printing cylinder, and means for cleaning that offset cylinder which is in inactive position at the time. 20
7. In an offset copying machine, a frame, a printing cylinder, a slide mounted for reciprocation in the frame, a pair of offset cylinders 25 mounted on the slide, a crank shaft, a pinion splined on the crank shaft, a toothed sector on the printing cylinder whose length is equal to one-half of the pinion's perimeter, manually operated means including a slide and a cam on 30 the slide for shifting the pinion into mesh with the sector, a crank on the crank shaft, a double-armed lever having a cam slot adapted to be engaged by the crank in one of its arms and 35 operatively connected to the slide with its other arm for shifting the slide for alternately moving one of the offset cylinders into active position with respect to the printing cylinder, and means for cleaning that offset cylinder which 40 is in inactive position at the time. 40

LEO KLUITMANN.
